UNITED STATES PATENT OFFICE.

CONRAD SCHMITT, OF MILWAUKEE, WISCONSIN.

DESIGN FOR A HANGING LANTERN.

Application filed November 21, 1927. Serial No. 24,213. Term of patent 7 years.

To all whom it may concern:

Be it known that I, CONRAD SCHMITT, a citizen of the United States, residing at Milwaukee, in the county of Milwaukee and State of Wisconsin, have invented a new, original, and ornamental Design for Hanging Lanterns, of which the following is a specification, reference being had to the accompanying drawings forming a part thereof.

Fig. 1 is a side perspective of a hanging lantern, showing my new design, and Fig. 2 is a diagrammatic cross section for the purpose of showing contour.

I claim:

The ornamental design for a hanging lantern, substantially as shown.

CONRAD SCHMITT.
